UNITED STATES PATENT OFFICE

WILSON B. WIGLE, OF LOS ANGELES, CALIFORNIA

HYDRAULIC ROTARY UNDERREAMER

Application filed June 11, 1927. Serial No. 198,117.

This invention relates to oil well drilling tools and more specifically to underreamers.

It is a chief object of the invention to provide an oil well reaming tool that may be readily lowered through a well casing in a contracted position into the well hole and then expanded into an operative reaming position.

Other objects and advantages will be apparent in the following specification, reference being had to the accompanying drawing forming a part thereof, in which:

Fig. 1 is a vertical section through a portion of an oil well with a casing in the upper end, the reaming tool being illustrated in connection with a drilling bit.

Fig. 2 is a view similar to Fig. 1 showing the bit replaced with the reamer expanding element in an inoperative position being lowered through the casing.

Fig. 3 is a view similar to the foregoing showing the reamer lowered below the casing with the expanding element in an operative position.

Fig. 4 is a side elevation of the reamer expanding element.

Fig. 5 is a cross section through the expanding element taken on line 5—5 of Fig. 4.

In an embodiment of the invention disclosed herein, 5 designates a cylindrical body member having the usual central water course 6 formed therein, provided on its upper end with the usual tapered threaded socket 7 for the reception of the threaded pin 8 secured to the lower end of the drill tube 9. The body member 5 is provided in its cylindrical wall with a rectangular recess 10 for the reception of a reaming tool 11, that is rotatably mounted on a shaft 12 whose ends are journaled in the end walls 13 and 14 of the recess, see Fig. 3; tool 11 is substantially cylindrical in form tapering from its central portion to its ends, and provided on its surface with cutting teeth 15 of any preferred form. From an inspection of the figures of the drawing, it will be seen that the cutting or reaming tool is disposed at an angle to the longitudinal axis of the body member 5, in order that the cutter will progres-

sively increase the diameter of the hole as the tool descends downwardly.

In Fig. 1 the tool is illustrated in connection with a drilling bit of the "fish tail" type for reaming the well hole simultaneously with the drilling operation, while the tool may be satisfactorily employed in this manner oftentimes it may be found to be advantageous to first drill the well and then enlarge the diameter of the hole, and to this end in Figs. 2 and 3 is illustrated a form of tool in which a hydraulically operated bearing shoe is substituted for the drill bit.

In this form a cylindrical body member 20 is employed provided on its upper end with a tapered threaded attachment pin 21, and the usual central water-course 22. The lower end of member 20 is bevelled as at 23 from a point to one side of the vertical axis upwardly and outwardly and is provided with a dove-tail tongue 24 that engages a corresponding groove 25 formed in the contacting inclined face of a bearing shoe 26. The tongue 24 extends upwardly and terminates just below a transversely disposed bore 27 that connects with the bottom of the water course 22 that registers with the course 6 of member 5, and the groove 25 in the shoe terminates short of the upper end to form an abutment 28 for moving the shoe into an operative position as will be more fully explained hereinafter.

The outer vertical face of the shoe is provided with a plurality of transversely disposed grooves or water courses 29 for preventing any sticking action of the shoe during the operation of the tool.

Secured to the upper end of the inclined or bevelled face of member 20 in any suitable manner is a stop 30 designed to limit the upward movement of the shoe and to bring the transverse bore 31 of the shoe into register with the transverse bore 27 leading from the water course 22 when the shoe is in operative position.

Should it be found desirable to enlarge the diameter of the well to permit the lowering of the string of casing the tool can be readily lowered through the casing as the shoe 26 is retracted to its lowermost position and will

form no impediment to the passage of the tool therethrough (see Fig. 2). When the tool is disposed beyond the lower end of the casing the pumps (not shown) are put into operation to force water downwardly through the central water course, the pressure of the water against the abutment 28 raising the shoe to the position shown in Fig. 2, the outer face of the shoe extending beyond 10 the peripheral face of the member 20, thereby forcing the cutter 15 into engagement with the wall of the well. When in this position it will be apparent that on a rotation of the tool that the cutter will be forced into engagement with the wall of the well and will readily and quickly ream the same to the required diameter. As soon as the reaming is completed, the water pressure is relieved, whereupon the shoe will slide back into its 20 normal inoperative position, and the tool may then be withdrawn from the well.

When the shoe is moved to an operative position the bore of the shoe will be brought into register with the central water course 25 of the body member, thus insuring an adequate supply of water for lubrication and washing away of the well cuttings. Further the shoe will be maintained in operative position during the rotation of the reaming tool 30 by the fluid pressure acting against the abutment.

What I claim is:

1. A rotary hydraulic well reaming tool comprising a cylindrical body member provided with a water course, a reaming cutter mounted on said body member adapted to engage with the wall of the well, and a hydraulically operated shiftable bearing member secured to the body member for forcing the 40 reamer cutter into cutting engagement with the well wall, said shiftable member having a fluid port adapted to register with the water course of the body member when said member is shifted.

45 2. A rotary well reaming tool comprising a body member provided with a water course therethrough, a cutting member mounted on the wall of the body member, a shiftable bearing member secured to the lower end of said body member having a fluid port adapted to register with the lower end of the water course of the body member when in operative position, and hydraulic means for expanding the expandable member into engagement with the wall of the well, whereby the reaming cutter will be forced into cutting engagement with the wall of the well to increase its diameter.

50 3. A rotary hydraulic well reaming tool comprising a body member provided with a water course, a cutter member rotatably mounted in the wall of the body member, a bearing shoe movably secured to the lower end of the body member, and fluid pressure 55 means for expanding said shoe to force the

cutter into engagement with the wall of the well.

4. In a well reaming tool, a cylindrical body member having a water course, a cutter tool rotatively mounted in a recess formed 70 in the wall of said body member, and a shiftable fluid actuated bearing shoe mounted on the end of said body member, the outer face of said shoe when shifted upwardly extending beyond the peripheral surface of the body member. 75

5. In a well reaming tool, a cylindrical body member provided with a water course, a substantially cylindrical cutter tool rotatably mounted in the wall of said body member adapted to engage the wall of the well when the body member is rotated, and a bearing shoe slidingly mounted on the lower end of said body member having a water discharge bore therein adapted to register with the water course of the body member when the shoe is moved to an operative position, and fluid pressure means for operating said shoe. 80

6. In a well reaming tool a body member provided with a water course, a wall cutting tool mounted for rotation in the wall of the body member, a wall bearing shoe slidingly mounted on the lower end of said body member having a bore adapted to register with the water course of the body member when brought into operative position, said shoe having a recess on its inner face above the bore, whereby when fluid pressure is introduced through the water course of the body member the shoe will be moved upwardly into operative position, the fluid pressure maintaining the shoe in engagement with the wall of the well during the operation of the reaming tool. 90

7. A rotary well reaming tool comprising a body member provided with a water course therethrough, a bearing shoe having a fluid discharge port adapted to register with the water course when the shoe is moved to operative position secured to said body member, and fluid pressure means for moving the bearing shoe into engagement with the wall of the well prior to a well reaming operation. 100

8. A rotary well reaming tool comprising a body member provided with a water course therethrough, a bearing shoe having a recess adapted to register with the water course when the shoe is in an inoperative position secured to said body member, and fluid pressure means discharging through the water course into the shoe recess for moving the bearing shoe into engagement with the wall of the well prior to a well reaming operation. 110

9. A rotary hydraulic well reaming tool comprising a body member provided with a water course, a side wall cutting member secured to the body member, a shiftable shoe normally disposed adjacent the lower end of 120 125 130

said body member, and fluid pressure means for shifting said shoe upwardly to force the cutting member into engagement with the wall of the well.

5 10. In a well reaming tool, a cylindrical body member having a water course therethrough, a reaming cutter secured to said body member for enlarging the bore of the well as the drilling progresses, and a fluid actuated bearing shoe shiftably mounted and normally disposed at the lower end of said body member, the outer face of said shoe when shifted upwardly extending beyond the peripheral surface of the body member to 10 force the reaming cutter into engagement with the wall of the well.

15 11. In a well reaming tool, a cylindrical body member having a water course therethrough, a reaming cutter secured to said body member for enlarging the bore of the well as the drilling progresses, and a bearing shoe shiftably mounted on the lower end of said body member having a water discharge bore therein adapted to register with the 20 lower end of the water course of the body member when the shoe is shifted, and fluid pressure means for shifting said shoe upwardly into engagement with the wall of the well.

25 12. In a well reaming tool, a cylindrical body member having a water course therethrough, a reaming cutter secured to said body member for enlarging the bore of the well as the drilling progresses, a wall bearing shoe shiftably mounted on the lower end of said body member having a bore adapted to register with the water course of the body member when brought into operative position, said shoe having a recess on its inner 30 face above the bore, whereby when fluid pressure is introduced through the water course of the body member the shoe will be shifted upwardly into operative position with the wall of the well, the fluid pressure maintaining the shoe in said operative position during 35 the operation of the reaming tool.

40 In testimony whereof I affix my signature.
WILSON B. WIGLE.
